SUPPORTING AND POSITIONING DEVICE
FOR CHAIRS AND THE LIKECarl Furrer, Zug, Switzerland, assignor to Landis
& Gyr, A.-G., Zug, Switzerland, a corporation
of SwitzerlandApplication June 28, 1930, Serial No. 464,439
In Switzerland July 12, 1929

1 Claim. (Cl. 155—94)

The invention relates to novel and useful improvements in height or position varying means applicable to chairs and other objects wherein rapid, easy and simple height variations and other 5 positionings are desirable.

Objects and advantages of the invention will be set forth in part hereinafter and in part will be obvious herefrom, or may be learned by practice with the invention, the same being realized and 10 attained by means of the instrumentalities and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:—

Fig. 1 is an elevation, with parts in section, of a chair embodying one form of the invention;

Fig. 2 is an enlarged, horizontal section on line 2—2 of Fig. 1, showing the height adjusting means 25 in locked position;

Fig. 3 is a like view to Fig. 2, showing the adjusting device in unlocked position;

Fig. 4 is an enlarged, fragmentary, detached 30 vertical sectional detail of parts shown near the center of Fig. 1;

Fig. 5 is an elevation, partly in section, of a chair embodying a different form of the invention;

Fig. 6 is an enlarged, horizontal section on line 35 6—6 of Fig. 5, showing the height adjusting means in locked position; and

Fig. 7 is an enlarged, detached, vertical sectional view of parts shown near the center of Fig. 5, and showing the locking device in unlocked 40 position.

The invention provides novel position varying means, especially height varying means, applicable to chairs and other articles needing, and adaptable to, similar positional variations. In 45 certain aspects, the invention provides such means having especial applicability to chairs and the like.

The invention provides position varying means 50 of the kind described which are substantially automatic in operation in effecting the position changing operation, in that little need be done more than to move the object to the desired position, a slight additional movement of the object sufficing to unlock the holding means and to re-lock it to hold the article in the new position. In

addition, position varying means having the described characteristics are provided which are of very simple and sturdy construction, having few parts and operating in a very simple and reliable manner, and requiring no direct or manual manipulation of the holding or locking means.

Referring now in detail to the embodiment of the invention illustrated by way of example in the accompanying drawings, the invention is shown applied to a chair, and in certain of its features it has special application as a chair positioning means. In said exemplary showing, further, the locking device is shown in two forms; one form wherein it is gravity-operated, and the other form wherein it is spring-impelled.

Referring by way of example to said illustrated embodiment including the gravity-impelled locking means, reference is had to Figs. 1 to 4. In said figures a chair is shown having a seat and a frame 2 between which the variable positioning means are located and interact. Supported in fixed position upon, and projecting upwardly from, the frame 2 is a vertical tubular shaft 3, within which slides a downwardly-dependent stem 4, fixed to the chair seat, and upon which the seat is supported. Stem 4 is likewise preferably hollow.

Referring now to the interacting locking devices, formed in the stem 4 are a plurality of positioning recesses 8, formed in the periphery of the stem, each of said recesses having the upper surface 9 thereof horizontal, or substantially horizontal, and having the lower surface 10 thereof inclined outwardly and downwardly. The recesses 8 correspond in number to the number and location of desired positions of the chair. Cooperating therewith on the tubular column 3 is a recess 15, which is inwardly and downwardly inclined.

In connection with the recess 15, retaining and guiding means are provided for a freely-moving locking member which is impelled by gravity into the locking position, and which is moved from locking position by simply lifting the chair. The locking member referred to is preferably a freely-rolling member, and is shown as a cylinder 16. Guiding and retaining means for the freely moving member 16 comprise a plate 17, fixed to, and projecting from, the column 3 and extending upwardly and outwardly from the lower portion of the recess 15. The member 16 may thus move into and out of the recess 15 and along the plate 17, between locking and unlocking positions. To retain member 16, at either side of the plate 17 are upwardly and inwardly-extending walls 19,

which extend inwardly to, and engage with, the sides of the column 3. The outer portion of the plate 17 is turned up at either side, as shown at 20 and 21, to constitute part of the retaining 5 means for the locking member 16. Between the turned up portions 20 and 21 is an opening 22, through which the locking member may be introduced or withdrawn.

If the stem 4 is solid with the chair seat 1, the 10 mechanism will serve to hold the chair in a predetermined position, i. e., against free rotation.

This feature is frequently of advantage in various occupations, such as the operation or attendance upon certain machines. On the other hand, 15 if a swivelling effect is desired, this may be effected by suitable means such as providing an ordinary swivel joint 11 between the chair seat 1 and the stem 4.

In the operation of the embodiment just described, the parts are shown in locking position in 20 Figs. 1 and 2. It will be seen that as soon as one of the recesses 8 in the stem 4 passes into alignment with the recess 15 in the column 3, the rolling member 16 will pass into the recess 8, and will 25 form a supporting and locking member, due to its position in the particular recess 8 and the recess 15, and member 16 will support and lock the chair, or the like, in desired position. If it is desired to lift the chair one or more notches, the rolling 30 member 16 will be moved upwardly and outwardly by engagement with the downwardly and outwardly slanting bottom surface 10 of the particular recess 3 in which it is engaged, and it will roll upwardly along the plate 17 until it is clear of the 35 stem 4. That is, it will move from the position of Figs. 1 and 2 to that of Fig. 3, when it is clear of the stem 4. It will continue to do this, or to be in this position, so long as the chair is lifted. When the chair is released, it tends to settle by the 40 action of gravity, and the rolling member 16 is permitted to roll downwardly along the plate 17 and inwardly in the recess 15, and will enter one of the recesses 8 in the stem 4. The upper surface 45 9 of the recess 8 will rest thereon, the rolling member being interlocked in recesses 8 and 15, and the chair is supported or locked into desired position, as shown in Figs. 1 and 2.

When it is desired to lower the chair, or the like, it is slightly lifted, and in the manner already 50 described the rolling member 16 passes out of the recess 8 and rolls upward along the plate 17, until clear of the stem 4. Thereupon the stem 4 is rotated approximately 90 degrees, whereby the series of recesses 8 are moved out of register with the rolling member 16, which is then maintained 55 in unlocking position by the solid periphery of the stem 4. The chair may then be lowered to any desired position, the stem 4 sliding freely within the column 3. When the desired position is 60 reached, the chair is rotated again to the position shown in Fig. 2, and the rolling member again passes into interlocking position with the recesses 8 and 15 in the manner previously described,

thereby supporting and locking the chair in position.

In Figs. 5 to 8, an embodiment is exemplarily shown wherein the locking device is both held in position and impelled to locking position by resilient means, such as a spring. This obviates the necessity for the retaining and guiding means shown in the other exemplary embodiment already described. The general structure of the chair and frame may be as in the other embodiment, and need not be again described. The rolling member 16 is acted upon by resilient means, shown herein as a coil tension spring 27. As embodied, grooves 28 and 29 are formed in either end of the rolling member 16, and the spring 27 has terminal hooks 29 and 30 hooking over the grooved portions of the member 16, the tension spring passing about the exterior of the hollow column 3.

In operation the spring both holds the locking member 16 in position and impels it to locking position. The operation is otherwise as already described. That is, when a recess 8 on the stem is in register with the recess 15, the spring draws the member 16 inwardly, and it moves downwardly in the recess 17 and into the registered recess 8, and the top surface 9 of the recess rests upon the member 16 and the chair is thereby supported. When the chair is lifted upwardly, the downwardly and outwardly inclined surface 10 of the recess moves the member 16 backwardly against the tension of its spring until it passes outside the periphery of the stem 4, the chair being thereby rendered freely movable. When a recess 8 on the stem is brought into register with the recess 15, the member 16 is drawn inwardly by its spring, in the manner previously described, and is again in locking and supporting position. By imparting a quarter-rotation to the stem 4 when the member 16 is outside the periphery thereof, the chair or the like may be lowered to any desired position, and by subsequent rotation in the opposite direction, the locking movement may be again effected as already described.

The invention in its broader aspects is not limited to the exact constructions herein exemplarily shown and described as embodiments thereof, but changes may be made in said structures, within the scope of the accompanying claims, without departing from the principles of the invention or sacrificing its chief advantages.

What I claim is:—

A chair including in combination a seat, a stem for the seat, a frame part in which said stem is vertically movable, an open slot formed in said frame part, notches spaced apart on said stem, a detent member slidable in said slot, said slot being of sufficient depth to completely receive said detent member and a coiled spring encircling said frame part and secured to the opposite ends of said detent for urging said detent inwardly through said slot and into one of said notches to hold the seat and stem at the desired height.

CARL FÜRER.
